UNITED STATES PATENT OFFICE.

PAUL M. BEARD, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

DRAFT-GEAR:

1,199,755.

Specification of Letters Patent.

Patented Oct. 3, 1916.

Application filed June 10, 1912. Serial No. 702,844.

To all whom it may concern:

Be it known that I, PAUL M. BEARD, residing at St. Louis, Missouri, and being a citizen of the United States, have invented 5 certain new and useful Improvements in Draft-Gear, of which the following is a full, clear, and exact description, such as will enable others skilled in the art to which it appertains to make and to use the same, 10 reference being had to the accompanying drawings, which illustrate the preferred form of the invention, though it is to be understood that the invention is not limited to the exact details of construction shown 15 and described; as it is obvious that various modifications thereof will occur to persons skilled in the art.

In said drawings: Figure 1 is an isometric perspective view illustrating my improved 20 draft gear applied to a draft sill with a part of the front stop casting broken away and with one draft sill removed. Fig. 2 is a horizontal sectional view, the section being taken on line 2—2 of Fig. 3. Fig. 3 is a 25 vertical sectional view, the section being taken on line 3—3 of Fig. 2. Fig. 4 is a transverse vertical sectional view, the section being taken on line 4—4 of Fig. 3 looking in the direction indicated by the arrow. 30 Fig. 5 is a transverse vertical sectional view, the section being taken on line 5—5 of Fig. 3, looking in the direction indicated by the arrow. Fig. 6 is a view taken relatively on the line 5—5 of Fig. 3, looking in the direction opposite to that indicated by the arrow; that is, rearwardly.

Referring to the parts, F indicates the draft sills, H the coupler shank, G the front follower of the draft gear, I the rear follower 40 lower of the draft gear, B B' the yoke extensions of the rear follower and S the key extending transversely through slots in the yoke and through the registering slot in the shank of the coupler to yieldingly connect 45 the draft gear to the coupler. The front and rear followers are each provided with pockets 1, in which are seated springs 2, which are preferably arranged vertically one above the other, so as to utilize, as far as 50 possible, springs of maximum capacity, the springs being arranged in any desired manner, as, for instance nested in the pockets 1 of the front and rear followers, as indicated in Fig. 2 of the drawing, which drawing is

intended to represent standard F.M.C.B. 55 construction.

It will be observed that the draft gear provided includes a combined draft yoke and rear follower with a front follower movable on and within the arms B-B' of the yoke, the front follower being wider near the top than it is near the bottom, shoulders 5 projecting laterally therefrom and resting upon the yoke extensions B-B', as best shown in Figs. 1 and 5, in which it will 65 be observed that the spring pockets are of approximately uniform area and the front follower rides on the yoke extension B-B', the lower spring pocket being formed in a relatively narrower portion of the spring 70 follower than the upper spring pocket. This is an advantage in assembling the draft gear.

As will be noted in Figs. 1, 2 and 3, the rear follower I is provided with a rearwardly projecting shoulder or bracket 6 connected by flanges 7 with the rear follower and being formed integral with said rear follower as a unitary casting, though it is obvious that this bracket may be separately formed and subsequently applied to the rear follower, if desired. Coöoperating with the bracket 6 is a transversely extending key 8, which projects through the draft sills F and through the webs of the rear 85 stops or draft lugs 9, which draft lugs are preferably provided with flanges 10 extending from the front, top and bottom edges of the draft lugs, as best shown in Fig. 1, and the draft lugs are secured in 90 position by rivets 11, passing through the webs of the draft lugs and the webs of the draft sills F.

Owing to the depth of the front and back followers, it is desirable to provide 95 proper bearings therefor, extending below the plane of the draft sills. The rear follower abuts against the draft lugs 9, and to provide suitable area for the connection of the large draft lugs 9, angles 11^a are riveted 100 to and depend from the lower flanges 12 of the draft sills, so that the bottom portion of the draft lugs 9 may be riveted to the depending legs of the angles 11^a, which angles 11^a, should extend longitudinally of 105 the draft sills a sufficient distance to afford proper rivet connection thereto.

The front follower G contacts with the

rear face of the coupler shank, which coupler shank is indicated by dotted lines in Fig. 4, and plays between the downwardly extending portions 13 of the front stop casting 14, which, as shown in Figs. 1 and 3, extends forwardly from the front follower G to or in the vicinity of the ends of the draft sills F, in the present instance being shown flush with the ends of such draft sills, thereby forming a combined front follower stop and striking casting, and by reason of the direct rivet connection of the casting 14, through its vertical flanges 15, with the webs of the draft sills, it serves as a draft sill tie and brace for the draft sills.

Below the draft sills and forwardly of the front follower, I provide an abutment for the lower portion of the front follower, comprising a flanged rolled section 16, which may be of any form, though it is shown as an I-shape in cross section turned horizontally, which section is connected by the supporting plate or pressing 17 in contact with the depending brackets 18, which are riveted to the bottom flanges of the draft sills, as best shown in Figs. 3 and 5, from which it will be noted that the brackets 18 extend rearwardly of the front follower G at each side thereof to provide proper rivet connection of the brackets 18 with the draft sills.

The draft gear illustrated and described is assembled in the usual manner with the springs under some compression, after which it is placed in position and the key 8 is passed through registering openings or slots in the draft sills and draft lugs below the bracket 6, thus affording suitable support for the rear end of the draft gear, after which the coupler shank may be placed in position and the front key S is projected through registering openings in the draft sills, the yoke extensions B B', and the rear portion of the coupler shank H, the openings in the draft sills and yoke extensions being longer from front to rear than the width of the key S, so as to provide a relatively yielding connection between the coupler shank and the draft gear when the parts are assembled.

In operation, it will be noted that the rear face of the coupler shank will abut the forward face of the front follower, and to as-

sist in assembling I provide on the front face of the front follower, an integral lug or extension 20, which is adapted to enter a registering opening commonly incident to cast coupler shanks, thus providing means for properly positioning the coupler shank before passing the key S through the parts before mentioned. The coupler shank opening referred to is an incident resulting from coring in common practice. As will be evident from the drawings, the buffing stresses will be transmitted from the coupler to the front follower and through the draft springs, the rear follower abutting the draft lugs 9, which, as will be noted in Fig. 3, are in close proximity to the forward edges of the bolster bottom cover plate 21, intermediate plate 22 and center bearing casting 23; and in pulling, owing to the key connection S, pulling stresses will be transmitted from the coupler through the key, the yoke extensions B B' and rear follower to the draft springs, which will cause the front follower to abut against the stop casting 14 and the bracket members, before referred to, below the draft sills. Such play longitudinal of the underframe as may be incident to service will be permitted the rear follower by reason of the rearward extension of the bracket 6, which at all times in service rests upon the key 8, and it will be noted that owing to the shoulders 5 of the front follower resting on the yoke extensions the front follower is properly supported in position without the usual follower straps commonly employed in spring draft gears.

What I claim is:—

A pair of draft sills, a striking casting consisting of an upper front draft follower stop and an abutment constituting a lower front draft follower stop, brackets secured to the draft sills and forming supporting plates for said abutment, said brackets being extended rearwardly of the front follower at each side thereof.

In witness whereof I have hereunto set my hand in the presence of two witnesses.

PAUL M. BEARD.
